UNITED STATES PATENT OFFICE

2,468,666

PRODUCTION OF VARIABLE DENIER RAYON

Gustav Anton Maria Heim, deceased, late of Velp, Netherlands, by Clementine H. H. Heim-Hoedemakers, executrix, Velp, Netherlands, assignor to American Enka Corporation, Enka, N. C., a corporation of Delaware

Application November 12, 1946, Serial No. 709,112
In Germany March 27, 1942

Section 1, Public Law 690, August 8, 1946
Patent expires March 27, 1962

8 Claims. (Cl. 18—8)

1

This invention relates to the production of rayon yarn having denier variations and is more particularly concerned with the production of rayon yarn having zones of low denier occurring at regular intervals along its length.

In the production of synthetic yarns having denier variations, it is customary to lengthen the filament strands of freshly spun rayon between the spinnerette and the draw off roller by periodically, sharply pushing the yarn out of its normal path with a cam or the like. Ordinarily, the cam is driven by a mechanism entirely divorced from the extrusion or draw off apparatus with the result that denier variations which are not correlated with the rate of yarn travel are produced. Accordingly, the product produced by prior art apparatus is characterized by objectionable lack of uniformity and its cost is increased due to the complexity of the apparatus used for imparting the denier variations thereto.

It is an object of this invention to overcome the disadvantages of prior art apparatus for the production of rayon yarn having denier variations and provide simple and inexpensive apparatus for the production of regularly occurring thin spots in the yarn which may be used as tear points in the production of staple fibers.

Other objects and advantages of this invention will be apparent upon the consideration of the following detailed description in which:

Figure 1 is a diagrammatic view in side elevation of a single spinning position equipped with apparatus constructed in accordance with the present invention for producing regularly occurring denier variations in the yarn;

Figure 2 is a view in front elevation of the apparatus of Figure 1;

Figure 3 is a detailed view showing one position of a cam that is employed in imparting denier variations to the yarn; and

Figure 4 is another view of the cam of Figure 3 in a different position.

Referring now in greater detail to the drawings, the yarn issuing from a spinnerette 10 is led upwardly through a thread guide 11, in tangential contact with a pair of closely spaced rollers 12 and 13 arranged in vertical alignment, over the roller 13, and under an adjacent laterally spaced roller 14 from which the yarn is led to a draw off surface 15 of a stepped godet 16 which includes also a larger draw off surface 17 and a sloping guide roller 18. After passage around the surface 15 of the godet 16, the yarn is led again over the roller 14 from which it passes around the surface 15 again, then over the guide roller 18, then

5 around the surface 17 of the godet 16, then around a sheave 19, then over the surface 17 again and finally to a point of collection or after-treatment, not shown. A panel 20 is provided on which the rollers 12, 13 and 14, as well as the sheave 19, are mounted.

It will also be noted that the axis of the sheave is slightly horizontally offset with respect to the yarn path between the rollers 12 and 14. Accordingly in this offset and attached to the sheave 19 for rotation therewith, is a cam 21 provided with a sharp cam surface 22 adapted to engage and displace the yarn passing between rollers 12 and 13, see Figures 3 and 4.

15 By the disposition of the cam adjacent the yarn path between closely spaced rollers 12 and 13, and by driving the sheave 19 by a loop from the draw off godet, the cam 21 is driven by the yarn and accordingly, produces regular denier variations during the passage of the yarn between the rollers 12 and 13, see again Figures 3 and 4.

The location of the roller 14, spaced from, but in the same horizontal plane as the roller 13, results in imparting to the yarn a very marked 25 change in direction in its passage between roller 14 and the surface 15 of the stepped godet 16. This change in direction causes the cam produced stretch to take place between the spinnerette 10 and the roller 13 while the thread is 30 still quite soft and deformable and prevents the stretch from being felt to any appreciable extent between the roller 13 and the godet 16. It is also desirable that the cam 21 be located as near as possible to the spinnerette 10 and that the yarn 35 drive the sheave 19 so that the cam 21 rotates with, rather than against, the direction of yarn travel.

What is claimed is:

1. Apparatus for the production of yarn having denier variations comprising a spinnerette, a draw off device for drawing yarn from the spinnerette, means for periodically altering the length of the yarn path between said spinnerette and said draw off device to impart denier variations to said yarn, and means directing said yarn, after the denier variation has been imparted thereto, in driving relation to said length-altering means.

2. Apparatus for the production of rayon yarn having denier variations comprising a spinnerette, a draw off device for drawing yarn from the spinnerette, a mechanism including a cam for periodically altering the length of the yarn path between said spinnerette and said draw off device to impart denier variations to said yarn, and means directing said yarn, after the denier varia-

tion has been imparted thereto, in driving relation to said cam.

3. Apparatus for the production of rayon yarn having denier variations comprising a spinnerette, a draw off device for drawing yarn from the spinnerette, a pair of spaced rollers in the yarn path between said spinnerette and said draw off device, yarn driven means for periodically altering the length of the yarn path between said rollers to impart denier variations to the yarn, and means directing said yarn, after the denier variation has been imparted thereto, in driving relation to said length-altering means.

4. Apparatus for the production of rayon yarn having denier variations comprising a spinnerette, a draw off device for drawing yarn from the spinnerette, a pair of spaced rollers in the yarn path between said spinnerette and said draw off device, a yarn driven cam for periodically altering the length of the yarn path between said rollers to impart denier variations to the yarn, and means directing said yarn, after the denier variation has been imparted thereto, in driving relation to said cam.

5. Apparatus for the production of rayon yarn having denier variations at regular intervals along its length comprising a spinnerette, a first draw off means, a second draw off means and rotatable means including a driving sheave for altering the length of the yarn path between said spinnerette and said first draw off means, the driving sheave of said rotatable means lying in the yarn path between the first and second draw off means whereby the rotatable means is driven by the yarn at a rate correlated with the rate of yarn travel.

6. Apparatus for the production of rayon yarn having denier variations at regular intervals along its length comprising a spinnerette, first and second draw off means, a pair of spaced rollers in the yarn path between said spinnerette and said first draw off means and a cam including a driving sheave for altering the length of the yarn path between said rollers, the driving sheave of said rotatable means lying in the yarn path between said first and second draw off means whereby the cam is driven by the yarn at a rate correlated with the rate of yarn travel.

7. Apparatus for the production of rayon yarn having denier variations at regular intervals along its length comprising a spinnerette, draw off means, a pair of vertically spaced rollers, a third roller laterally spaced from said pair of rollers, all of said rollers lying in the yarn path between said spinnerette and said draw off means, said third roller lying close to said pair of rollers in the yarn path between said pair and said draw off device, and yarn driven means for periodically altering the length of the yarn path between the rollers of said pair.

8. Apparatus for the production of rayon yarn having denier variations at regular intervals along its length comprising a spinnerette, first and second draw off means, a pair of spaced rollers disposed vertically above the spinnerette in the yarn path between the spinnerette and the first draw off means, a third roller laterally spaced from said pair of rollers and lying in the yarn path between said pair of rollers and said first draw off device in closely spaced relation to the former, and a cam for altering the length of the yarn path between said pair of rollers, said cam having a driving sheave lying in the yarn path between said first and second draw off means whereby the cam is driven by the yarn at a rate correlated with the rate of yarn travel.

30 CLEMENTINE H. H. HEIM-HOEDEMAKERS,
Executrix of the Estate of Gustav Anton Maria Heim, Deceased.
